UNITED STATES PATENT OFFICE.

JAMES F. THOMAS, OF MONTREAL, QUEBEC, CANADA.

PUMPING MECHANISM.

Application filed October 27, 1921. Serial No. 510,917.

To all whom it may concern:

Be it known that I, JAMES F. THOMAS, a subject of the King of Great Britain, residing at Montreal, Province of Quebec, Canada, have invented certain new and useful Improvements in Pumping Mechanism, of which the following is a specification.

This invention relates to pumping mechanism particularly adapted and constructed

10 for compressing air, elevating or forcing water after the manner of a ram for use in various capacities as a power generating medium, or for general service or supply,

15 provide a comparatively simple organization of cooperating elements of the rocking or oscillating type and including a prime factor in the form of a cylinder in which a

piston is loosely mounted to freely recipro-

20 cate in opposite directions, and thereby dis-

pose with piston connecting or controlling

devices and rely solely for positive actuation

of the piston on the gravitation thereof al-

ternately from one end to the other of the

25 prime factor or cylinder to accomplish the

desired operation relatively to charges of air

or water that may be indrawn into the cyl-

inder, or on any other medium to which

the improved mechanism is adapted. A fur-

30 ther object of the invention is to provide

a mechanism of the class specified comprising

as a prime factor a cylinder fulcrumed for rocking or oscillating movement and

having a piston mounted therein for free

35 gravitating action, the cylinder and piston

being provided with means for at all times

maintaining a tight joint, to avoid leakage

and to render the piston effective in its com-

pressing or forcing action relatively to the

40 medium that may be indrawn into the cyl-

inder. A still further object of the invention

is to provide a mechanism of the class

specified, including a prime factor or cyl-

45 inder having a piston mounted to freely recip-

rocate therein through gravitating action

thereof to automatically charge and dis-

charge the cylinder, and to have in connec-

50 tion with the cylinder positive driving means

that will insure regular rocking or oscilla-

55 tion movement thereof alternately in opposite

directions and to such an extent as to effect

a full stroke of the piston in the respective

operations of charging and discharging the

55 cylinder.

With these and other objects and advan-

tages in view, the invention consists in the

construction and arrangement of the several parts which will be more fully hereinafter described and claimed.

In the drawings:

Fig. 1 is a side elevation of a mechanism embodying the features of the invention and showing the prime factor or cylinder in dotted lines in full rocked position in one direction;

Fig. 2 is a longitudinal vertical section through the cylinder, a part of the support for the cylinder being shown;

Fig. 3 is a transverse vertical section on the line 3—3, Fig. 2, on an enlarged scale;

Fig. 4 is a horizontal section of one ex- tremity of the cylinder, showing the piston at the limit of its stroke and illustrating the intake and discharge pipes, the parts being shown on an enlarged scale;

Fig. 5 is a top plan view of the shifting mechanism for controlling the reverse operation of the driving chain belt, the pulley band being shown in section;

Fig. 6 is a top plan view of the cylinder and intake and discharge pipes shown on the same scale as in Fig. 1, the driving mechanism being in part omitted;

Fig. 7 is a detail elevation showing a portion of the shifting mechanism.

The numeral 5 designates a supporting pedestal or frame comprising opposite members 6 having supporting feet 7 and reduced towards their upper ends, to provide means for applying suitable bearings 8 thereto for opposite trunnions 9 fixed to a prime operating factor or cylinder 10 having therein a freely movable and operatively unrestrained piston 11 of suitable dimensions and weight. At opposite ends of the cylinder 10 are laterally projecting heads 12 for attachment of discharge and intake pipes or conduits 13 and 14, the discharge pipe or conduit connected to opposite heads 12 being provided with a central discharge outlet 15, and the intake pipe or conduit 14 having a central inlet connection or member 16 adapted to be attached or run to a source of supply of water, or be open to the atmosphere for free passage of air thereinto and into the intake.

The discharge and intake pipes 13 and 14 connect with both ends of the mechanism or with the heads 12, to adapt the mechanism for reversal of operation or oscillation in a manner which will be more fully here- inafter explained, and while water and air may be referred to as the medium acted

upon by the improved mechanism in the subsequent description, it will be understood that the improved mechanism is intended for use with any other liquid or service to which it may be applicable. Each of the heads 12, as clearly shown by Fig. 4, has loosely mounted valves 16 and 17 disposed in operative alinement with the connected terminals of the discharge and intake pipes 10 or conduits 13 and 14 and operating alternately in reverse directions, or, when the valve 16 is opened, the valve 17 will be closed, and vice versa. Each of the heads 12 is formed with an interior chamber 18 and within this chamber is a projecting valve seat 19 of suitable structure for the valve 16, the valve 17^a also having a seat 20 in alinement with the connected terminal of the intake pipe or conduit 14. The valves 17 and 17^a are mounted to operate in a supporting member 21 extending longitudinally of the head, and in view of the projection of the valve seat 19 for the valve 17, the said member is a greater distance outwardly from the said seat than it is from the seat 20 for the valve 17^a. The valves 17 and 17^a have stems 22 and 23 which are mounted in suitable guides 24 located in the centers of the connected terminals of the pipes or conduits 13 and 14, and said stems also have means for preventing the valves from turning, as will be readily understood by those skilled in the art. The valves 16 and 17^a are free to move, or are unrestricted by springs or other obstructing devices and operate solely through the action of the piston 11 in its reverse movements through the cylinder 10, so that the pressure of the said piston towards the valve 17 will open the latter and the pressure or force created within the chamber 18 when the piston moves towards the valve 17 will close the valve 17^a, and conversely, when the piston moves in the opposite direction it sets up a drawing action on the valve 17 to close the latter, and likewise, on the valve 17^a to open the same or move it into the chamber 18, so that a charge of water or air may be drawn into the cylinder 10 by the suction created due to the movement of the said piston. The member 21 is of such construction that the intake and discharge by means of the opposite connected terminals of the pipes or conduits 14 and 13 will be practically effected without interference. The connected terminal of the discharge pipe 13 relatively to each head 12 is separated from the connected terminal of the intake pipe 14 to the head by an intermediate partition 25, and it is proposed to supply the interior of each head with a filling or wall of suitable plastic material, as at 26, and this plastic structure will be carried out relatively to the valve seats, so that the valves operating upon or contacting or engaging with the said plastic fillings or walls will form their own seats and maintain tight joints relatively thereto. The interior of the cylinder 10 at the top and sides are likewise provided with walls 27 and 28 of suitable plastic material, and the base of the cylinder consists of a metal plate 29 extending the full length thereof and formed with longitudinal grooves 30 on opposite sides of the center, and a central smaller groove 31 wherein are first inserted a plurality of screws 32 to which reinforcing wires or analogous devices 33 are secured and run lengthwise of the grooves, the latter then being supplied with plastic fillings 34 varying in depth in accordance with the depth of the grooves, said fillings being pressed into the grooves and imbedding the heads of the screws as well as the wire reinforcement. The grooves are practically semi-circular in cross sectional contour, as shown by Fig. 3, and the plastic fillings 34 are flush with the upper surface of the plate 29. The purpose of these plastic fillings 34 is to reduce the friction at the bottom of the cylinder, so that the piston may have greater freedom of action, or will not be restricted by any tendency to stick or jam during its movement. The top and side plastic walls 27 and 28 of the cylinder are also conducive to the reduction of friction to a minimum and provides for a free action of the piston 11 during its reciprocating operation in alternation longitudinally of the cylinder 10. To the bottom of the piston 11 track plates 35 are secured and have depending inverted triangular ribs 36 extending longitudinally thereof, to fit in correspondingly shaped grooves 37 in the base plate 29 of the cylinder, these track plates and ribs together with the grooves 37 maintaining the piston 11 in true position within the cylinder and preventing the same from laterally wobbling or becoming displaced, and thereby insuring a regularity of wear on the plastic walls of the cylinder. The interior of the cylinder 10, after it has been provided with the plastic top and side walls 27 and 28, is trued and rendered snug relatively to the piston 11, by supplying the latter temporarily with face plates at opposite ends, which operate to cut or smooth out the said walls or the interior of the cylinder to such dimensions as to permit the piston to have free sliding movement, but at the same time insure a reasonably tight sliding fit. After the interior of the cylinder 10 is trued and the piston 11 given a snug fitting relatively thereto, the face plates may be removed from the opposite ends of the piston. In order to prevent leakage past the piston, or between the latter and the walls of the cylinder, plastic packings 37^a are applied therearound, as shown by Fig. 2, and fitted in grooves 38, 130

these packings as they wear down by constant movement of the piston 11 being adapted to be replaced, so as to maintain a tight joint between the walls of the cylinder and the piston. As shown in Fig. 2, the packings 37^a are positioned at opposite extremities of the track plates 35 and bear, respectively, on the fillings 34 at the bottom and top and side plastic walls 27 and 28. The purpose of the screws and reinforcing wires engaging the plastic fillings 34 is to insure retention of said fillings within the grooves in the event that the walls of the grooves become rusted, which would thereby cause the plastic fillings without the said retention means to loosen and create irregular operation or jam the piston in the cylinder. All the parts of the cylinder as well as the head 12 will be reinforced by suitable structural devices extending therearound, such as bands 39 and bolts or rods 40 and analogous strengthening means. The cylinder 10 is centrally fulcrumed relatively to the members of the pedestal 5, so that if the piston 11 was disposed centrally within the cylinder, or to project equally on opposite sides of the vertical center thereof, the said piston and cylinder would equally balance, but it will be understood that when the piston shifts from one end to the other of the cylinder, the preponderance of weight towards one end will cause the cylinder and piston to rock and be depressed at one end and elevated at the opposite end.

In order to provide tell-tale means for the cylinder and piston, especially when the mechanism is used to intake and discharge water or other liquid, an auxiliary attachment 41 is provided and consists of a glass or transparent receptacle or chamber 42 having a top supply connection 43 that may run from any source, the said glass or transparent chamber 42 also having an outlet pipe 44 extending from the bottom thereof and through the top portion of the cylinder 10 into a counter recess 45 formed in the top plastic wall 27, the said recess providing a small chamber for the distribution of the contents of the chamber 42 along the top of the piston 11 and filling the spaces particularly between the plastic packings 37^a. This auxiliary device will serve as a tell-tale to indicate any unusual leakage, and in this instance the contents of the chamber 42 will rapidly flow into the cylinder and escape around the piston if there be a leak, and an operator will know by observing the chamber 42 and its contents whether or not the piston is properly working without leakage, or in the event of leakage, repair can be made, or the plastic packings 37 may be replaced, to restore the non-leaking association of the piston with the cylinder. The bolts or rods 40 extend through the sides of the cylinder as shown by Figs. 3 and 4, and

in addition the cylinder walls are provided with a reinforcing wire gauze structure, as at 40^a. It is proposed to reinforce the cylinder 10 at any other points that may be found necessary in order to strengthen the same.

Various mechanisms for operating the cylinder 10 might be adopted whereby the said cylinder will be regularly oscillated to effect a gravitation of the piston 11 towards opposite ends of the cylinder in alternation, but one preferred form of operating mechanism consists of an endless chain belt 46 attached to arms 47 projecting outwardly from the opposite extremities of the lower portion of the cylinder 10 and then passing downwardly over a lower idler sprocket 48, at the center of the lower portion of the pedestal, as shown by Fig. 1. The endless chain belt 46 extends upwardly over a sprocket wheel 49 loose on a drive shaft 50 and having a clutch hub 51 integral therewith. On the shaft 50 a band pulley 52 is keyed and engaged by a belt 53 running from a pulley 54 on an upper power shaft 55 that may be a line shaft of a machine shop or other mechanical institution. On the shaft 50 adjacent to the band pulley 52 is a bevel gear 56 in alignment with an opposing similar bevel gear 57 adjacent to or forming part of the sprocket wheel. The gear 56 is also loose on the shaft 50 and between the two gears 56 and 57 is a transmission bevel gear 58^a. The gear 56 also has a toothed clutch hub 58, and between the two hubs 51 and 58 a clutch sleeve 60 is splined to and slidable on the shaft 50, and whereby the motion of this shaft may be transmitted to either the gear 57 and the sprocket wheel adjacent thereto, or the gear 56, the reversal of movement of the main driving sprocket wheel and the gear 57 being accomplished through the interposed gear 58. The clutch sleeve is shifted to alternately change the direction of movement of the chain belt 46 by a yoke 61 having a depending arm 62 with a lower fork 63 formed with suitably bent terminals 64 for engagement by strikers 65 projecting from the arms 47 or some other part of the cylinder structure, and whereby when the cylinder 10 is thrown up at one end, as shown in dotted lines by Fig. 1, the clutch sleeve 60 will be shifted through the forked extremity or end 64 to change the direction of movement by bringing different gearing into play and to cause the cylinder and piston to be thrown over from the dotted position shown in Fig. 1 to the reverse position, or so that the end or extremity of the cylinder that is uppermost as shown in dotted lines in Fig. 1 will be lowermost, and this oscillation continues during the actuation of the chain belt through the gear and mechanism explained, and the cylinder will be regularly actuated and the

piston automatically shifted in alternation from one end to the other of the cylinder. The improved cylinder and piston are double acting in that an intake and discharge is effected at opposite extremities in an automatic and positive manner. It will also be understood that the chain belt 46 will have sufficient slack to render it effective in operation of the cylinder and piston and also 10 to accommodate it to varying positions of the latter during the rocking movement or oscillation thereof.

It is obvious that changes in the proportions and dimensions and minor details of 15 construction of the several parts may be adopted at will without departing from the scope or spirit of the invention.

What is claimed as new is:

1. In a mechanism of the class specified, 20 a rocking cylinder having interior plastic walls and provided with intake and discharge connections at opposite ends, the intake and discharge connections being provided with reversely opening valves, a piston 25 ton freely slideable in the cylinder and operable by gravitating movement thereof alternately towards opposite ends of the cylinder, the cylinder and piston being angular in contour and having a snug relative fit, a single pipe connection for each inlet and outlet at opposite ends of the cylinder, and means for rocking the cylinder, piston and connections as a unit.

2. In a mechanism of the class specified, 35 a rocking cylinder formed with walls of plastic material having strengthening means associated therewith and also provided at each end with an intake and discharge opening, the intake and discharge opening 40 at one end of the cylinder being respectively connected to the intake and discharge openings at the opposite end of the cylinder by pipes each having a single opening therein, a freely slideable piston mounted within the 45 cylinder and operable solely by gravitation thereof towards opposite ends of the cylinder to alternately open and close the valves at the intake and discharge openings at each end of the cylinder, the cylinder 50 and piston being angular in contour and having a snug relative fit, and means for insuring an invariable longitudinal movement of the piston.

3. In mechanism of the class specified, a 55 rocking cylinder formed with walls of plastic material having transversely extending heads laterally projecting to one side of opposite ends of the cylinder and provided with interior chambers and passages to 60 form intake and discharge openings which have communication with the said chambers, the said intake and discharge openings being provided with reversely moving valves and the intake and discharge openings of one head being respectively con-

nected by pipes to the same openings of the opposite head, the pipes each being provided with a single opening therein, a piston mounted to freely slide in the chamber and operable solely by gravitation towards 70 opposite ends of the cylinder, the chamber and piston being angular in contour and having a snug relative fit, and means for rocking the cylinder, piston, heads and intake and discharge connections as a unit 75 alternately in opposite directions.

4. In mechanism of the class specified, a rocking cylinder having interior plastic walls and provided with intake and discharge connections at opposite ends, and a piston freely slideable in the cylinder and operable by gravitating movement thereof alternately towards opposite ends of the cylinder, the cylinder and piston being angular in contour and having a snug relative fit.

5. In mechanism of the class specified, a rocking cylinder having interior plastic walls and intake and discharge connections, and a piston mounted to freely slide in the 90 cylinder and provided with plastic packings disposed on opposite sides of the center and surrounding the piston to engage the plastic walls of the cylinder.

6. In mechanism of the class specified, a 95 rocking cylinder having grooves in the bottom thereof and provided with intake and discharge connections, and a piston mounted to freely slide in the cylinder and operable solely by gravitation, the piston having 100 lower ribs to engage the said grooves to maintain the piston in positive operating position within the cylinder.

7. In mechanism of the class specified, a 105 rocking cylinder having plastic walls and a metal bottom with grooves extending longitudinally thereof, intake and discharge connections at opposite ends of the cylinder, a piston mounted to freely slide in the cylinder and having plastic packings to engage the walls of the cylinder and the metal bottom, plates secured to the lower portion of the piston and having ribs to engage the 110 said grooves, and means for actuating the cylinder.

8. In mechanism of the class specified, a 115 rocking cylinder having interior plastic walls, the upper wall having a counter recess therein, a piston mounted to freely slide in the cylinder and having plastic packings to engage the walls thereof, and an auxiliary charging attachment having a supply connection opening into the said counter recess to effect a liquid charge between the said packings and the adjacent 120 wall of the cylinder, the said auxiliary charging attachment serving also as a tell-tale to indicate leakage between the piston and the walls of the cylinder.

9. In mechanism of the class specified, a 125

rocking cylinder having transversely extending chambered heads at opposite ends provided with intake and discharge openings which have communication through the chambers of the heads, the said intake and discharge openings having plastic walls, a valve loosely disposed in each of the said openings and having a stem projecting outwardly therefrom, the valve engaging the plastic walls and all of the valves operated

in alternation, snug seats for the valves being formed in the plastic walls by the movement of the valves, and a piston mounted in the cylinder and serving to alternately open and close the valves in the said chambered heads. 15

In testimony whereof I have hereunto set my hand.

JAMES F. THOMAS.
